UNITED STATES PATENT OFFICE.

JOHN M. ROHLFING, OF PLAINFIELD, NEW JERSEY, ASSIGNEE TO AMERICAN CAR AND FOUNDRY COMPANY, OF NEW YORK, N. Y., A CORPORATION OF NEW JERSEY.

STRIPPER MECHANISM FOR PUNCHING PRESSES.

Application filed May 1, 1928. Serial No. 274,200.

This invention relates to punching presses and has as an object the providing of an improved stripper mechanism in which the stripper bar is positively held in engagement 5 with the work while the punches are being withdrawn from the work and is positively raised from the work after the withdrawal of the punches.

In the drawings:

10 Figure 1 is a partial end elevation of a punching press equipped with a stripper mechanism constructed in accordance with this invention;

15 Fig. 2 is an end elevation of the means for holding an end of the stripper bar in its lowermost position, other parts of the punching press being shown to show the relation of the holding means thereto;

20 Fig. 3 is a horizontal section of the holding means taken on the line 3—3 of Fig. 2;

25 Fig. 4 is an irregular vertical sectional view showing the stripper bar and guide bracket in section, the link, cam and clamping bar in side elevation, and

30 Fig. 5 is a vertical section taken on the line 5—5 of Fig. 4.

In the drawings, the invention is shown applied to a punching press having a stationary bed 1 and a movable head 2, dies 3 being 35 mounted on the bed 1 and punches 4 secured to the movable head 2 in the usual manner. Extending from side to side of the press is a stripper bar 6 having notches 8 adjacent each end thereof and flanges or ears 10 projecting from the bar 6 on both sides of each notch 8 on one side of the stripper bar. Mounted between the flanges 10 of each notch 35 is an extension member or arm 12 having a nose or lug 14 engaging in the notch 8, the 40 arm 12 being held in engagement with the stripper bar 6 by bolts 16 which are inserted in alined openings in the flanges 10 and arms 12. The lugs 14 and the stripper bar 6 at the notches 8 are provided with alined openings 45 17 and 18 respectively, the openings 18 being of uniform diameter throughout, while the openings 17 are partly of the same diameter as the openings 18 and partly of a lesser diameter, thereby forming shoulders 19.

45 Loosely mounted in the openings 17 and 18 are bolts 20 having heads 21 which engage with the shoulders 19 and having their threaded ends projecting through openings in the movable head 2 and secured therein by 50 nuts 22. This construction furnishes a lost

motion connection between the movable head 2 and the stripper bar 6 which permits of the stripper bar engaging the work before the punches 4 do and of remaining in contact with the work until after the punches 60 have been disengaged therefrom.

Secured to the body 1 at each side thereof is a guide bracket 23 comprising a base 24 which rests upon the bed 1 and is provided with openings 25 which receive the securing 65 bolts 26 and spaced parallel sides 27 which project perpendicularly to the base 24 and are provided at their upper ends with inwardly projecting flanges 28 which with the connecting web 30 form a guide slot for the reception 70 of the guide flanges 32 formed on the opposite sides of each arm 12.

The lower ends of the arms 12 are bifurcated to form the jaws 34 in which are pivotally mounted the ends of clamping bars 36 75 which extend between the sides 27 of the guide brackets 23 and have their other ends which are rounded as at 37 movably supported on wear plates 38 inserted in openings 80 in bases 24 of the guide brackets 23.

Mounted in openings in bosses on the sides 27 of the guide brackets 23 are pins 40 on which triangular shaped cams 42 are mounted between the sides 27. The cams 42 are provided at one corner thereof with openings in 85 which are mounted the pins 44 which are secured in the cams by set screws 45 and project on both sides of the cams 42. The pins 44 engage in slots 46 in jaws 48 formed in the lower ends of links 50 which have their upper 90 ends rotatably mounted on pins 52 carried by brackets 54 secured to the movable head 2 by bolts 55.

Assuming the parts to be positioned as shown in Fig. 4, operation of the movable 95 head 2 to cause the punches 4 to act on the work 56 (shown in broken lines) will also lower the stripper bar 6 until it rests on the work 56 carrying with it the arms 12 and the bars 36 until the bars 36 are substantially in 100 engagement with the base of the guide bracket 23. This movement of the head 2 also lowers the links 50 which at first permit the cams 42 to rotate on the pins 40 until the cams 42 engage the bars 36, and during the last portion 105 of their movement, the links 50 force the cams 42 into engagement with the bars 36 so as to secure the bars 36 in the position shown in Fig. 1. In case a cam 42 binds and does not rotate upon the first downward movement of 110

the link 50, the guides 58 on the sides 27 of the guide bracket 23 guide the lower end of the link 50 outwardly and guide the link in forcing the cam to rotate. When the movable head 2 is raised to withdraw the punches from the work 56, the lost motion connections between the bolt 20 and the stripper bar 6 and between the link 50 and the cam 42 permits the withdrawal of the punches 4 from the work 56 before the heads 21 of bolts 20 engage with the shoulders 19 and before the links 50 operate the cams 42, thus insuring the stripper bar being held in engagement with the work 56 and holding the work upon the dies 3 and preventing the lifting of the work by the binding of the punches 4 in the openings in the work. Further upward movement of the head 2 causes the links 50 to operate the cams 42 to release the bars 36 and causes the heads 21 of bolts 20 to engage with the shoulders 19 and to raise the stripper bar 6 from the work 56.

While the preferred embodiment of the invention has been shown and described, it is to be understood that the invention is not limited to the exact details of construction shown and described, as it is obvious that various modifications thereof within the scope of the claims will occur to persons skilled in the art.

What is claimed is:

1. In a punching press having a movable head, a stripper bar carried by said head, a clamping bar connected to said stripper bar and a cam operated by said head to engage said clamping bar and prevent movement of said stripper bar.
2. In a punching press having a stationary bed and a movable head, a stripper bar carried by said head and having a lost motion connection therewith, a clamping bar connected to said stripper bar, a cam, and an operative connection between said cam and head having a lost motion therein, said cam engaging said clamping bar to hold said stripper bar on said bed during the taking up of the lost motion by said head.
3. In a punching press having a stationary bed and a movable head, a stripper bar carried by said head, a clamping bar pivotally connected to said stripper bar and bearing on said bed, and a cam operated by said head and engaging said clamping bar to hold said stripper bar to said bed.
4. In a punching press having a stationary bed and a movable head, a stripper bar carried by said head, an arm secured to said

stripper bar, a clamping bar pivotally connected to said arm and slidably supported on said bed, a cam pivotally mounted on said bed and operated from said head to engage said clamping device.

5. In a punching press having a stationary bed and a movable head, a stripper bar carried by said head, an arm secured to said stripper bar, a clamping bar pivotally connected to said arm and bearing on said bed, a cam pivotally mounted on said bed, and a link forming a lost motion connection between said cam and head and operating said cam to engage and disengage said clamping bar upon movement of said head.

6. In a punching press having a stationary bed and a movable head, a stripper bar carried by the movable head, an arm secured to said stripper bar, a clamping bar pivotally connected to said arm and bearing on the stationary bed, and a cam operated from said movable head and engaging said clamping bar, to hold said stripper bar in engagement with the work.

7. In a punching press having a stationary bed and a movable head, a stripper bar carried by said movable head, an arm secured to said stripper bar and movable therewith, a clamping bar pivotally connected to said arm and bearing on said stationary bed, a cam rotatably mounted on said stationary bed, and a link connected to said movable head and cam and operating said cam to engage said clamping bar to hold said stripper bar against movement.

8. In a punching press having a stationary bed and a movable head, a stripper bar carried by said head and having a lost motion connection therewith, an arm secured to said stripper bar, a guide bracket for said arm mounted on said bed, a clamping bar pivotally connected to said arm and slidably supported on said bed, a cam pivotally mounted on said guide bracket and engaging said clamping bar when rotated, and a link carried by said head and having a lost motion connection with said cam to rotate said cam into engagement with said clamping bar.

9. In a punching press having a vertically reciprocable head, a stripper bar carried by said head, a clamping bar connected to said stripper bar and a cam operatively connected to said head and engaging said clamping bar to prevent movement of said stripper bar.

In witness whereof I have hereunto set my hand.

JOHN M. ROHLFING.
